STOP MECHANISM FOR CARD-SORTING MACHINES.

1,177,651.

Specification of Letters Patent.

Patented Apr. 4, 1916.

Application filed April 4, 1913. Serial No. 758,774.

To all whom it may concern:

Be it known that I, JAMES POWERS, a citizen of the United States, residing in New York city, in the county of New York and State of New York, have invented certain new and useful Improvements in Stop Mechanisms for Card-Sorting Machines, of which the following is a specification.

The object of my invention is to provide an automatic apparatus which will detect card-feed irregularities in card-sorting machines, and stop or suspend their operation until such irregularities are rectified. It may be described in general terms as comprising a detector and stop member operably connected with the pin box and with the transmission or driving mechanism of such a machine, and adapted to co-act with normally-fed cards to permit continuous operation and in case the card-feed is interrupted or made irregular, by any cause, to suspend the supply of power to or the operation of the drive-mechanism of such machines, until their card-feed is again made normal. The successful operation of this device will greatly facilitate the operation of such machines and increase their duty by instantly detecting card-feed irregularities and limiting their pernicious effects to the primary stages of the process.

In the drawings, Figure 1 is a partial side view of a card-sorting machine with my stop mechanism operably connected therewith and its members in normal operating positions. Fig. 2 is an enlarged side view of my stop mechanism with its members shown in stop and normal positions, respectively, by full and dotted lines. Fig. 3 is a right hand end view and Fig. 4 an opposite end view of my stop mechanism with its members normally located; Fig. 5 is a partial end view like Fig. 4 but with the members in stop position, and Fig. 6 is a perspective diagram illustrating the relations of the levers.

Fig. 1 illustrates the card-feed end of a card-sorting machine, with its frame 2, magazine 1, main shaft 10, and some principal members of its card-sorting mechanism, such as the pin-box 24, the sorting pins 39, the pin-plates 25 and 26, the gears (adjacent to said plates) which drive the feed rolls, boxes

m, n, for sorted cards, and exterior members of the card-deflecting mechanism, as the deflector shafts, cranks and crank rods 55 respectively 73, 72 and 63, the co-acting trip arm 61, the retractor bar 70, and its operating connection with its cam 126 on the main shaft 10.

The pin-box 24 is illustrated as mounted 60 on an open frame 24^a, slidable in parallel guides 24^b, and as reciprocated by a cam 104 on the main shaft 10; said cam, for convenience, being a suitably-contoured groove formed in the body of the cam 126, which 65 actuates the retractor 70, the pin box 24 being engaged with said cam 104 by means of a roller 24^c, pin-mounted on the head, 24^c, of the pin-box mounting frame 24^d.

The stop apparatus S comprises a card 70 controllable detector member S¹, a work-suspending apparatus S²⁰, and connecting apparatus S⁴⁰, operably connecting the aforesaid members. The detector S¹ is illustrated in its simplest form as a bent rod 75 (Fig. 2) pivotally connected at its lower exterior end with a primary lever S⁴¹ of the connecting apparatus, thence extending vertically above and inwardly over the pin-plates and having an inner, downwardly extending pin S² adapted to be reciprocated in a hole 25^a in the upper pin plate 25, and to extend its end across and to withdraw it clear of the card-path 164^p between said plate and its mate, 26, in which a registering hole 26^a is made for the traverse of the pin S². If the lower pin-plate 26 could be as conveniently approached as the upper one, 25, the pin S² might point upwardly and reciprocate in the hole 26^a. The essential condition is that it move through the card path 164^p.

The primary lever S⁴¹ is suitably fulcrumed on a frame S²² and has a short arm which functions with other members of the connecting apparatus S⁴⁰, and a long arm on which the detector S¹ is pivoted and which, exterior thereto, has a positioning-limiting connection with the frame 24^a, the mode of which is not material, it being illustrated as by means of a position-limiting limb S⁴² on said lever (the upper end of a slot in the head thereof) and a frame pin, 24^p, on the frame 24^a. Their weight and an

auxiliary spring S^{43} tend to retract the lever S^{41} and the detector S^1 , and to cause the pin S^2 thereof to traverse the card-path 164°.

- 5 When the machine is sorting, the pin-box 24, frame 24^a and sorting pins 39, are reciprocated by the cam 104, and the frame pin 24^b plays idly in the primary lever slot S^{42} , except when near and at the upper limit 10 of such reciprocation (coinciding in time with the lift of the sorting pins 39 and if card-feed be normal, with the passage of the anterior edge of a card under the raised detector pin S^2), at which times the pin 15 24^b contacts with the upper end of said lever slot, S^{42} (said slot functioning only by said end, as a positioning shoulder or limb) and positions and upholds the detector S^1 , so that its pin S^2 will be flush with or slightly 20 above the under face of the upper pin-plate 25, and the card-path 164° between the plates 25 and 26 will be unobstructed.

If card-feed be normal a card is at such times fed between the holes 25^a and 26^a in 25 the pin plates and under the detector pins S^2 ; and when the sorting pins 39, pin box 24, frame 24^a and frame pin 24^b move into, and in, the upper part of their reciprocation, said card positions and upholds the 30 detector pin and detector, and thereby positions my stop apparatus normally, (Fig. 1) so that the power-supply to and the operation of the sorting machine are uninterrupted. If, on the contrary, card feed be 35 interrupted or abnormal, no card will be fed beneath the uplifted detector pin S^2 , and when the pin-frame 24 and its accessories descend, there being no supporting means to support the detector-pin S^2 , it can traverse 40 the card-path 164° and enter the hole 26^a in the lower pin plate; the spring S^{43} will draw down the primary lever and its short arm will be oppositely moved and permit the stop apparatus S to move to stop 45 position (Fig. 2, full lines) and the power supply to the sorting machine or its operation, or both, will be suspended.

The drawings illustrate stop apparatus adapted to an electrically-driven sorting 50 machine. Therefore the function-suspending apparatus S^{20} is illustrated as of the most effective and simplest nature, i. e., a circuit breaker, S^{21} , and as comprising an open frame or box S^{22} adapted to mount 55 and to be bench assembled with the other members of my stop apparatus and therewith mounted, as a unit, on the sorting machine frame 2, and when so mounted to operably locate the detector pin S^2 relatively 60 to the holes 25^a and 26^a and the positioning shoulder S^{42} of the primary lever S^{41} relatively to the coacting frame member 24^b; forked poles S^{23} supported and insulated in 65 said frame and having binding post S^{24} to which ends of the electric conduit S^{25} are at-

tached, and a switch knife S^{26} , provided with heads S^{26} adapted to be entered between the forks of and contact with the poles S^{23} , to complete, and to be withdrawn therefrom to break the circuit. The electric 70 circuit is conventional and comprises the generator, rheostat and the motor which drives the sorting machine, none of which present novel features and are therefore not illustrated.

75 The preferred means for positioning and operating the switch knife S^{26} follow: I provide a switch lever S^{27} suitably fulcrumed in the frame S^{22} and having a short arm terminating in a positioning head S^{28} , a long sector-arm S^{29} on which the switch knife S^{26} is insulated, and a radial slot S^{30} in the sector arm S^{29} . A switching rod, S^{32} , is slidably mounted in bearings in the frame 80 2, in a plane adjacent to that of the sector arm S^{29} , is armed with a pin S^{31} which engages the slot S^{30} in said arm, and is provided with an exterior knob or handle S^{33} and a circuit-breaking spring S^{34} strained 85 between a projection on the switching rod 90 S^{32} and the frame S^{22} . The spring S^{34} tends to lift the switching rod S^{32} , because of its engagement with the switch lever S^{27} (by means of the slot S^{30} and pin S^{31}), to shift the switch and break the circuit (Fig. 2, full 95 lines).

I might position and release the switch 100 S^{27} by the primary lever S^{41} , but the subordinate members of my connecting apparatus S^{20} are a convenience and enable me to accomplish the desired movements of the latter with greater certainty and precision. I 105 therefore suitably fulcrum in the frame S^{22} , a bell-crank lever S^{44} , normally retracted to engaging position relatively to the switch by a spring S^{45} and having a switch-engaging socket S^{46} adapted to engage the head S^{28} of the switch-lever S^{27} , a long arm terminating in a suitable handle, and a short arm which terminates exterior to the frame 110 S^{22} and substantially opposite the end of the short arm of the primary lever S^{41} (the two levers being located in substantially parallel planes); and on said frame I fulcrum, centrally, a transverse lever S^{47} , the arms of 115 which are adapted to co-act with (in this instance ride) the short arms of the primary and bell-crank levers, S^{41} and S^{44} . When the apparatus is in normal position (Figs. 1 3, 4, 6, dotted lines of Fig. 2) the detector 120 S^1 is upheld, (either by a card under its pin S^2 , or by the pin 24^b when the pin box 24 and frame 24^a are near the upper limit of 125 their reciprocation) and normally positions the primary lever S^{41} with its long arm raised and its short arm depressed and normally serving as abutment beneath and positioning the transverse lever S^{47} with its far arm depressed and its near arm raised by the short arm of the switch-release lever S^{44} , 130

which is drawn by the spring S^{45} into normal position and, with its socket S^{46} , engages the positioning head S^{28} of the switch levers S^{27} and positions the latter with the heads S^{26} of the switch knife S^{25} in the slots of and completing the circuit between the poles S^{23} .

When the card feed is interrupted or abnormal and no card is beneath the detector pin S^2 , and the pin box 24 moves down, the spring S^{43} depresses the primary lever S^{41} ; the detector pin traverses the card path 16^p and enters the hole 26^a in the lower pin plate 26, the short arm of the primary lever rises and reverse-positions the transverse and the switch release levers S^{47} and S^{44} , and retracts the latter so that its socket S^{46} releases the positioning head S^{28} of the switch lever S^{27} ; whereupon the switch spring S^{34} raises the switch rod S^{32} whose pin S^{31} , by its engagement with the slot S^{30} in the switch lever S^{27} , raises the sector arm S^{29} thereof and the switch knife S^{25} , whose heads S^{26} are thus withdrawn from the poles S^{23} (Figs. 2 and 5, full lines), thereby breaking the circuit and suspending the supply of power to and the operation of the sorting machine.

My stop apparatus can be restored to its normal position and work resumed by pressing down the switch rod S^{32} (by its knob S^{33}), which will strain the switch spring S^{34} , swing the switch lever S^{27} , enter the switch knife heads S^{25} between the forks of the poles S^{23} and complete the circuit, while at the same time the positioning head S^{28} of the switch lever 27 will be engaged by the slot S^{46} of the bell-crank.

I provide manually operable means, S^{48} , to suspend and restore the operation of the sorting machine at the will of the operator. This comprises merely the addition to the parts necessary for automatic operation of an exterior extension or handle of the bell-crank S^{44} . If the operator swings said handle S^{48} from the position shown in dotted lines to that shown in full lines in Fig. 2, the switch lever will be released and work suspended as above described; and it may be resumed by depressing the switch-rod S^{32} .

It will be observed (Fig. 1) that the detector pin S^2 is located somewhat anterior to the transverse plane of a line of sorting pins 39. This is done in order that when a sorting pin of said line registers with a perforation in the first line thereof in a card, the edge of said card may be safely entered (and no more) under the detector pin S^2 . Further, the detector pin should be in a predetermined location relatively to the sorting pins; and because the latter should be in a predetermined relation to card controlling means, specifically, to a card stopping arm, such as is described in my previous applications. Such locating of detector S^2 is accomplished by mounting my completely-as-

sembled stop apparatus by means of its frame S^{22} , on the sorting machine frame 2, the frame 22 being proportioned to that end.

Having thus described my invention, I claim:

1. In combination with a sorting machine comprising a frame having two plates between which cards are fed to be there sorted, an automatic stop means comprising a pin, there being registering openings in said plates in which said pin may reciprocate, said pin being held in raised position when a card obstructs its passage from one opening to the other, an electric switch for controlling the driving means of said sorting machine, and means connecting said pin with said switch so that said switch will be disconnected when said pin is permitted to pass through said two plates due to the failure of a card to obstruct the passage of such pin.

2. In combination with a sorting machine comprising a frame having a support to which cards are fed to be there sorted, an automatic stop means comprising a pin, there being an opening in said support in alignment with said pin, said pin being held in raised position above said plate when the card obstructs its passage into said opening, drive control means for controlling the driving means of said sorting machine, and means connecting said pin with said control means so that the movement of said pin may operate said control means.

3. The combination with a sorting machine having a card analyzing support, of means for successively feeding cards to said analyzing support, card controllable means, work control means, means for successively reciprocating said card controllable means toward said analyzing support, the card controllable means being maintained in inoperative position when a card obstructs its passage, means connecting said card controllable means with said work control means, said card controllable means actuating said connecting means to initiate the operations of the work control means when a card fails to obstruct its passage, and said work control means adapted to control the work of the sorting machine to have its operation initiated by said card controllable means.

4. The combination with a sorting machine, means for successively feeding cards through said sorting machine, card arrestable means, work control means, means for successively reciprocating the card arrestable means across the path of movement of the cards while being passed through said machine, the card arrestable means being maintained in inoperative position when a card obstructs its passage, means connecting said card arrestable means with said work control means, said card arrestable means

actuating said connecting means to initiate the operations of the work control means when a card fails to obstruct its passage, and said work control means adapted to control the work of the sorting machine to have its operations initiated by said card arrestable means.

5. The combination with a sorting machine having a card analyzing support, of means for successively feeding cards to said analyzing support, a card positioned member, a work control member, positioning and releasing means operably connecting said card positioned member and work control member, means for successively reciprocating said card positioned member toward said analyzing support, said card positioned member being maintained in inoperative position when a card obstructs its passage, said card positioned member actuating said positioning and releasing means to initiate the operations of the work control means when a card fails to obstruct the passage of said card positioned member, said positioning and releasing means adapted to be positioned by said card positioned member to position and release said work control member, and said work control member being adapted to be so positioned and released to control the work of the sorting machine.

6. The combination with a card sorting machine, means for successively passing cards therethrough, a card positioned means, a circuit breaker, and means for successively reciprocating a card positioned means across the path of movement of the cards being passed therethrough, said card positioned means being maintained in inoperative position when a card obstructs its passage and to open the circuit breaker when a card fails to obstruct the passage of said card positioned means.

7. Automatic stop means for card-sorting machines, comprising a movable card-positioned member, a circuit breaker and positioning-and-release means operably connecting said card-positioned member and circuit-breaker, said card-positioned member being maintained in inoperative position when a card obstructs its passage and actuating said positioning-and-release means to open the circuit-breaker when a card fails to obstruct the passage of such card positioned member.

8. Automatic stop means for card-sorting machines, comprising a movable card-positioned member, a positioning connection between said member and a movable sorting member of a card sorting machine, a positioning-and-release member and a circuit-breaker, said card-positioned member adapted to move across a card-path in a sorting machine, and maintained in inoperative position when a card obstructs its

passage across said card path, and actuating said positioning-and-release member to open said circuit-breaker when a card fails to obstruct the passage of such card positioned member.

9. Automatic stop means for card-sorting machines, comprising a frame, a movable card-positioned member, a positioning-and-release member and a circuit breaker operably mounted in said frame, said frame adapted to be mounted on a card-sorting machine and when so mounted to operably locate said card positioned member relatively to a card-path in said sorting machine, said card-positioned member being maintained in inoperative position when a card obstructs its passage, and actuating said positioning-and-release member to open the circuit-breaker when a card fails to obstruct the passage of such card positioned member.

10. Automatic stop means for card-sorting machines, comprising a frame, poles adapted to be connected in an electric circuit insulated in said frame and, operably mounted thereon, a switch, a switch-opening spring, a manually-operable switch-closing rod, a switch positioning and release member, a spring connected therewith, a movable card-positioned member and a connecting member adapted to connect said card-positioned and said switch-positioning and release members, said frame adapted to be mounted on a card sorting machine and when so mounted to operably locate said card positioned member and a limb of said connecting member respectively in a card path and in the path of a movable card sorting member of said sorting machine.

11. Automatic stop means for card-sorting machines, comprising a frame, a switch, poles adapted to be connected in an electric circuit insulated in said frame and, operably mounted thereon, a spring-retained bell crank lever adapted to position and release said switch, a card positioned member, a primary lever on which said card positioned member is fulcrumed, and a secondary lever operably connecting said bell-crank and primary levers, said frame adapted to be mounted on a card sorting machine and when so mounted to operably locate said card positioned member and a limb of said primary lever respectively in a card path and in the path of a movable card sorting member of said sorting machine.

12. Automatic stop means for card-sorting machines, comprising card-controllable means, work-control means and automatically-and-manually operable positioning-and-release means operably connecting said card-controllable and work-control means, said card-controllable means being maintained in inoperative position when a card obstructs its passage, and actuating said

positioning-and-release means to initiate the operations of the work-control means when a card fails to obstruct the passage of such card controllable means, said work-control means adapted to control the work of the sorting machine and to be positioned and released by said positioning-and-release means, and the latter adjusted to be operated manually and automatically by said 10 crank-controlled means.

13. The combination with a sorting machine, means for successively passing cards therethrough, card controllable means, work suspending means, means for successively reciprocating said card controllable means across the path of movement of the cards being passed through the machine, said card controllable means being maintained in inoperative position when a card obstructs its 20 passage, means connecting said card controllable means with said work suspending means, said card controllable means actuating said connecting means to initiate the operations of the work suspending means

when a card fails to obstruct the passage 25 of the card controllable means, and said work suspending means adapted to control the work of the sorting machine and to have its operations initiated by said card controllable means.

14. In combination with an article feeding device having a support to which the articles are successively fed, a controllable means successively passing across the path of the articles being fed, a work-suspending 35 means, and means connecting said controllable means with said work-suspending means, said controllable means being maintained in inoperative position when an article obstructs its passage, and actuating 40 said connecting means to initiate the operations of the work-suspending means when an article fails to obstruct the passage of such controllable means.
